US0D1004773S

(12) **United States Design Patent** (10) **Patent No.:** **US D1,004,773 S**
Grinberg (45) **Date of Patent:** **** Nov. 14, 2023**

(54) **EVACUATION DEVICE FOR LASER TREATMENT**

(71) Applicant: **LUMENIS LTD.**, Yokneam (IL)

(72) Inventor: **Tal Grinberg**, Yokneam (IL)

(73) Assignee: **LUMENIS BE LTD.**, Yokneam (IL)

(**) Term: **15 Years**

(21) Appl. No.: **29/766,261**

(22) Filed: **Jan. 14, 2021**

(51) LOC (14) Cl. **24-02**

(52) U.S. Cl.

USPC **D24/170**; D24/107

(57) **CLAIM**

The ornamental design for an evacuation device for laser treatment, as shown and described.

DESCRIPTION

FIG. 1 is a rear perspective view of the new design for an evacuation device for laser treatment.

FIG. 2 is a front perspective view of the new design of FIG. 1.

FIG. 3 is a front view of the new design of FIG. 1.

FIG. 4 is a rear view of the new design of FIG. 1.

FIG. 5 is a left side view of the new design of FIG. 1.

FIG. 6 is a right side view of the new design of FIG. 1.

FIG. 7 is a top view of the new design of FIG. 1; and,

FIG. 8 is a bottom view of the new design of FIG. 1.

The broken lines in the drawings illustrate portions of the evacuation device for laser treatment that form no part of the claimed design.

1 Claim, 8 Drawing Sheets
